CLAMSHELL BUCKET

Filed Feb. 25, 1925

FIG. 1.

FIG. 2.

FIG. 3.

Inventor

Edward L. Harrington

By *W. L. L.* Attorney

UNITED STATES PATENT OFFICE.

EDWARD L. HARRINGTON, OF ERIE, PENNSYLVANIA, ASSIGNOR TO G. H. WILLIAMS COMPANY, OF ERIE, PENNSYLVANIA, A CORPORATION OF PENNSYLVANIA.

CLAMSHELL BUCKET.

Application filed February 25, 1925. Serial No. 11,514.

To all whom it may concern:

Be it known that I, EDWARD L. HARRINGTON, a citizen of the United States, residing at Erie, in the county of Erie and State of Pennsylvania, have invented new and useful Improvements in Clamshell Buckets, of which the following is a specification.

This invention is designed to improve the opening and closing of clam shell buckets and is of particular advantage with clam shell buckets of the wide opening type. Among the advantages of the invention are the small clearance required for the apparatus when closed, and the freedom from obstruction between the buckets when opened, together with the great simplicity and strength of construction. Other features and details of the invention will appear from the specification and claims.

20 The invention is illustrated in the accompanying drawings as follows:—

Fig. 1 shows a side elevation of the bucket in open position.

Fig. 2 a similar view with the bucket 25 in closed position.

Fig. 3 a partial bottom view with the parts in the position shown in Fig. 1.

1 marks the scoops, and 2 the scoop arms extending from the scoops. These have the 30 braces 3 making the arms rigid with the scoops and these arms are pivotally connected by pins 4 at their upper ends, the arms interlocking at the pivot in the usual manner. Corner bars 5 are pivotally connected 35 by pins 6 at the outer corners of the scoops and are secured together at their upper ends and provided with bell crank arms 7 which are pivotally connected by a pin 8.

Toggle links 9 are connected by pins 10 40 arranged in the corner bars at the angle of the bell cranks formed between the corner bars and the arms 7. The links 9 are secured together by a pin 11 and to a hoisting cross head 12. Holding lines 13 are secured 45 to the cross head and chains 14 extend from the cross head to the pins 10 limiting the swinging movement of the cross head relatively to the corner bars.

Closing levers 15 are pivotally connected 50 by pins 16 at their lower end. They are provided with hubs or bosses 17 intermediate their ends which are arranged between the scoop arms 2 and pivotally connected with the scoop arms by pins 18. The outer ends 55 of the closing levers 15 are in the form of

loops 19 forming an intervening slot in which are mounted the sheaves 20.

Closing lines 21 extend through guides 22 in the cross head 12 around sheaves 23. The sheaves 23 are journaled on pins 24 in the frame formed by the connection between the corner bars 5 at their upper end. The hoisting lines extend around the sheaves 20 and their ends are secured to a link 25 hung by means of a link 26 on the pin 8.

In the operation of the device, starting with the open position shown in Fig. 1, as the hoisting line is actuated it exerts pressure on the closing levers 15 and this pressure is communicated first in a relatively upward direction on the arms 2, the pins 16 forming a common fulcrum on which the levers turn. As the scoops close and the arms 2 swing upwardly the upper ends of the levers 15 swing toward each other and in the final closing movement the closing strain is communicated laterally on the arms 2 through the effort of the cables drawing the upper ends of the levers 15 together and with this closing movement of the levers 25 forcing a closing movement of the arms and scoops. It will be noted that with the scoop in closed position the upper ends of the scoop arms may be brought into close proximity to the upper ends of the corner bars— 80 in other words, the mechanism requires practically no space between the frame formed by the corner bars and the ends of the arms. Consequently the clearance of the scoop which is of importance in some situations is materially reduced. It will also be observed that in the open position the closing levers, which are below the arms, are very nearly in line with the arms and consequently offer practically no obstruction to 85 a lowering of the scoops into engagement with the material which is operated upon.

90 What I claim as new is:—

1. In a clam shell bucket, the combination of two scoops; scoop arms extending 100 from the scoops and pivotally connected; scoop actuating levers pivotally connected at their lower ends and pivotally connected intermediate their ends with the arms; and means operating on the upper ends of the 105 levers to actuate the scoops.

2. In a clam shell bucket, the combination of two scoops; scoop arms extending 110 from the scoops and pivotally connected; scoop actuating levers pivotally connected

at their lower ends and pivotally connected intermediate their ends with the arms between the pivotal connections of the arms and the scoops; and means operating on the 5 upper ends of the levers to actuate the scoops.

3. In a clam shell bucket, the combination of two scoops; scoop arms extending from the scoops and pivotally connected; 10 closing levers pivotally connected at their lower ends and pivotally connected intermediate their ends with the arms; and closing means acting on the upper ends of the levers.

15 4. In a clam shell bucket, the combination of two scoops; scoop arms extending from the scoops and pivotally connected; closing levers pivotally connected at their lower ends and pivotally connected intermediate their ends with the arms; and closing means acting on the upper ends of the levers comprising sheaves on the upper ends of the arms, and cable means operating on the sheaves.

20 5. In a clam shell bucket, the combination of two scoops; scoop arms extending from the scoops and pivotally connected;

closing levers pivotally connected at their lower ends and pivotally connected intermediate their ends with the arms; and closing means acting on the upper ends of the levers comprising a hoisting cable. 30

6. In a clam shell bucket, the combination of two scoops; corner bars pivotally connected to the scoops, said bars in the form of bell cranks pivotally connected at their upper ends; closing means acting on the scoops connected to the corner bars; and a holding line acting on the corner bars 35 each side of their pivotal connection.

7. In a clam shell bucket, the combination of two scoops; corner bars in the form of bell cranks pivotally connected to the scoops and to each other at their upper ends; closing means acting on the scoops and connected to the corner bars; and a holding line acting on the corner bars each side of 40 their pivotal connection through a toggle interposed between the holding line and the bell cranks.

45 In testimony whereof I have hereunto set my hand.

E. L. HARRINGTON.
